UNITED STATES PATENT OFFICE

JAMES BALTON, OF BALTIMORE, MARYLAND, ASSIGNOR TO JOSEPH SHAPIRO, OF BALTIMORE, MARYLAND

MACHINE FOR MANUFACTURING SPIRALLY WOUND STRAWS OR TUBES

Application filed July 29, 1932. Serial No. 626,104.

My present invention which relates principally to machines for making spirally wound straws from paper strips has for an object to improve the machines of the type described in my application Serial No. 618,759, filed June 22, 1932. Machines such as those to which my invention relates contain several necessary parts, namely a support, an endless spinning belt taken over a pair of spaced pulleys, one flight of the belt being wound around a mandrel on which the paper is spun by the belt into the form of a tube or straw; such machines further include a mechanism for applying glue to one or more of the strips of paper before the strips are wound on the mandrel, and a cutting mechanism for severing the continuous straw or tube into predetermined lengths as it leaves the mandrel; there is also provided a means for tensioning the belt so that it will function properly during the spinning act.

The tensioning means heretofore generally employed in machines of this kind comprises the slidable mounting of one or both pulley carrying heads and the provision of a manually operated screw device for moving the heads toward and from one another.

It is to the belt tensioning mechanism of the machine to which my present invention is particularly directed. Experience has shown that unless exactly the right tension is applied to the belt during the spinning operation, the tube will be longer or shorter for a given length of paper strip; accordingly as the tension is loosened or tightened beyond the normal. Furthermore, unless the proper tension at least is applied, the glued surfaces do not adhere properly and consequently the tube when it comes from the mandrel has weak places; thus the tensile strength of the finished tube is not uniform throughout and the weakened places leave possible air-passes through the wall of the tube and thereby render that section of it useless as a drinking straw.

Experience has also demonstrated that it is practically impossible for the attendant to keep the belt at exactly the right tension at all times. Therefore it is necessary to em-

ploy skilled operators in order to reduce the percentage of error as much as possible in view of the human equation.

My invention has for its principal object to provide a mechanism that is fully automatic for maintaining the spinning belt at all times under a predetermined tension without the necessity of the operator's attention or intervention, thereby overcoming the deficiencies which are inherent in those machines which require manual adjustment of the belt tension and, in consequence of my invention, there is provided a machine which will not only turn out a superior product but one on which unskilled labor may be employed to advantage.

Again, in those machines heretofore known, which depend on the skill of the operator to maintain the belt adjustment, the life of a belt is variable. The life of the belt depends in large measure upon the skill of the operator, for if the operator tightens the belt too much it will soon wear out or break. Therefore it is a further object of my invention to provide means materially to increase the life of the belt and thereby reduce maintenance charges with consequent reduction in the cost of manufacture of the straws or tubes.

Other objects of my invention will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:

Figure 1 is a plan view of a straw machine showing my invention in one of its embodiments.

Figure 2 is a section on the line 2—2 of Figure 1.

Figure 3 is a section on the line 3—3 of Figure 2.

Figure 4 is a section on the line 4—4 of Figure 3.

Figure 5 is a plan view, largely diagrammatic, illustrating another embodiment of the invention.

Figure 6 is an elevation of the mechanism shown in Fig. 5.

Figure 7 is a section on the line 7—7 of Figure 6.

In the drawings in which like numerals of reference designate like parts in all the figures, 1 is the bed of the machine which is supported on legs 2, and which supports the cross head 13 which carries the spinning mechanism. The spinning mechanism includes cross head slides 18 and 25 on which are respectively mounted pulleys 22 and 24, the latter pulley being driven from a vertical shaft 11 through suitable power transmitting mechanism including beveled gears 12 and shaft 32. The cross head 13 has ends 14 and 15 provided with guides 16 and 17 respectively on which the cross head slides 18 and 25 are mounted. The spinning mechanism also includes the spinning belt 42 one flight of which is wound around the mandrel 52 that is carried by a support 50 which is mounted on the bed 1. 53 is the glue applying mechanism and 104 the cutting mechanism which includes the straw receiving horn. All of the foregoing parts may be of the conventional construction or of the construction described in my application aforesaid.

In applying my invention to such a machine I provide a pair of parallel bars 157—162, the former being secured by cap screws 158 or in any other suitable way to the cross head slide 25, while the bar 162 is similarly secured at 163 to a bracket 160 that is in turn secured by suitable devices such as cap screws 161 to the cross head slide 18.

Each bar 157 and 162 carries a rack segment 159—164 respectively. These rack segments are guided in a suitable support 165 secured at 166 to the cross head 13 and provided with suitable guide ways 167 for the bars 162 and 157. Mounted in suitable bearings 168 in the support 165 is a shaft section 169 that carries a pinion 170, the latter meshing with the rack segments 159—164 whereby upon rotation of the shaft 169 the cross heads 18 and 25 are moved toward or from one another accordingly as the shaft is turned in one direction or the reverse. 171 is another shaft section journaled in a suitable bearing 173 mounted on the bed 1. The shaft 171 is provided with a socket portion 172 into which the end of the shaft section 169 projects and is pinned as best indicated in Figure 3.

Secured to the shaft section 171 is a sprocket 174 around which is passed a chain 177, the chain passing through openings 76 in the bed 1 as best shown in Figure 4. On one end of the chain is placed a suitable weight or other constant force applying in-

strumentality, while the other end of the chain is provided with a safety stop bar 178 to prevent the chain being pulled off the sprocket and also serving as a stop to prevent the cross heads from separating too far should the belt break. 70

175 is a handle in the form of a star wheel which is secured on the outer end of the shaft section 171 whereby that shaft section may be turned for a purpose presently explained. 75

If desired, instead of connecting the sprocket carrying shaft section directly to the pinion carrying shaft section, a worm and worm gear may be interposed so as to constitute a lock as it were to prevent any possible vibration of the machine causing a displacement of the cross head slides. This latter embodiment of my invention is best illustrated in Figures 5, 6 and 7 by reference to which it will be seen that the shaft section 169 is provided with a worm wheel 183 that meshes with a worm 182 on a shaft 181 which carries the sprocket 184 and the hand wheel 185. In this embodiment of the invention there is also provided a suitable support 180 for the portion of the shaft 169 which carries the worm wheel 183 and for the portion of the shaft 181 that carries the worm 182. In this construction the chain is indicated by 186 and the weight by 187. So far as described the manner in which my invention operates is as follows:

Assume that the belt has been placed 100 around the pulleys and one of the flights of the belt wound around the mandrel, as is customary. The weight 179 is so arranged as to exert a constant pressure tending to separate the cross head slides 18 and 25, 105 thereby applying a constant and definite tension to the belt 42. As the belt stretches in use the stretch will be taken up by the movement of the rack and pinion mechanism under the acting force of the weight. After 110 a belt has been used to a point where it will break, the weight 179 will naturally separate the cross heads to their maximum distance. However, by turning the handle 175 the cross heads may be brought together so as to 115 enable a new belt to be placed around the pulleys and mandrel, after which the operator lets go of the handle 175 and the machine is again ready for operation.

While I have described two embodiments 120 of the invention, it is obvious that numerous other modifications may be made without departing from the spirit of the invention and the scope of the appended claims.

What I claim is:

1. In a machine of the character described a support on which is mounted a mandrel, a horizontally disposed pair of belt pulleys and a belt passed around the pulleys and mandrel, in combination with a means to 130

- maintain a constant tension on the belt for the purposes described.
2. In a machine of the character described, a support on which is mounted a mandrel, a horizontally disposed pair of belt pulleys and a belt passed around the pulleys and mandrel and slideable supports for the pulleys, in combination with means continuously acting to separate said pulley supports and pulleys for the purposes described.
3. In a machine of the character described, a support on which is mounted a mandrel, a horizontally disposed pair of belt pulleys and a belt passed around the pulleys and mandrel, in combination with means continuously acting to separate said pulleys for the purposes specified.
4. In a spirally wound tube making machine, a mandrel, a horizontally disposed endless spinning belt wound around the mandrel, a horizontally disposed pair of belt pulleys, and means to apply tension constantly to said belt for the purposes stated.
5. In a spirally wound tube making machine, a mandrel, an endless spinning belt wound around the mandrel, a pair of belt pulleys, and means to apply tension constantly to said belt for the purposes stated, said means comprising slideable supports for the pulleys and continuously acting mechanism for applying a separating force between said slideable supports.
6. In a spirally wound tube making machine, a mandrel, an endless spinning belt wound around the mandrel, a pair of belt pulleys, and means to apply tension constantly to said belt for the purposes stated, said means comprising a connection between said slideable supports having provisions to effect movement of the supports toward and from one another and means continuously acting on said connection for applying a separating force between the pulley supports.
7. In a spirally wound tube making machine, a mandrel, an endless spinning belt wound around the mandrel, a pair of belt pulleys, slideable supports for the pulleys and means to apply tension constantly to said belt for the purposes stated, said means comprising rack bars carried by the supports, a shaft with a pinion connecting said bars and in virtue of which the rotation of said shaft will cause movement of said rack bars in one direction or the reverse accordingly as said pinion shaft is rotated in one direction or the reverse, and means continuously acting on said shaft to turn it in a direction to effect a separation of said pulleys for the purposes described.
8. In a spirally wound tube making machine, a mandrel, an endless spinning belt wound around the mandrel, a pair of belt pulleys, slideable supports for the pulleys and means to apply tension constantly to said belt for the purposes stated, said means comprising rack bars carried by the supports, a shaft with a pinion connecting said bars and in virtue of which the rotation of said shaft will cause movement of said rack bars in one direction or the reverse accordingly as said pinion shaft is rotated in one direction or the reverse, and means continuously acting to separate said pulleys and thereby maintain a constant tension on said belt, and manually actuated means to turn said shaft in the reverse direction.
9. In a spirally wound tube making machine, a mandrel, an endless spinning belt wound around the mandrel, a pair of belt pulleys, slideable supports for the pulleys and means to apply tension constantly to said belt for the purposes stated, said means comprising rack bars carried by the supports, a shaft with a pinion connecting said bars and in virtue of which the rotation of said shaft will cause movement of said rack bars in one direction or the reverse accordingly as said pinion shaft is rotated in one direction or the reverse, and means continuously acting on said shaft to turn it in a direction to effect a separation of said pulleys for the purposes described, said means comprising a sprocket and chain with an actuating weight on the chain.
10. In a spirally wound tube making machine, a mandrel, an endless spinning belt wound around the mandrel, a pair of belt pulleys, slideable supports for the pulleys and means to apply tension constantly to said belt for the purposes stated, said means comprising rack bars carried by the supports, a shaft with a pinion connecting said bars and in virtue of which the rotation of said shaft will cause movement of said rack bars in one direction or the reverse, accordingly as said pinion shaft is rotated in one direction or the reverse, and means continuously acting on said shaft to turn it in a direction to effect a separation of said pulleys for the purposes described, said means comprising a sprocket and chain with an actuating weight on the chain and a hand wheel on said shaft for turning it against the action of said weight.
11. In a spirally wound tube making machine, a mandrel, an endless spinning belt wound around the mandrel, a pair of belt pulleys, slideable supports for the pulleys and means to apply tension constantly to said belt for the purposes stated, said means comprising rack bars carried by the supports, a shaft with a pinion connecting said bars and in virtue of which the rotation of said shaft will cause movement of said rack bars in one direction or the reverse accordingly as said pinion shaft is rotated in one direction or the reverse, and means continuously acting on said shaft to turn it in a direction to effect a separation of said pulleys for the purposes described.

tinuously acting on said shaft to turn it in a direction to effect a separation of said pulleys for the purposes described, said acting means comprising a worm gear on said shaft, a worm shaft with a worm meshing with said worm gear and means continuously tending to turn said worm shaft in one direction.

12. In a spirally wound tube making machine, a mandrel, an endless spinning belt wound around the mandrel, a pair of belt pulleys, slideable supports for the pulleys and means to apply tension constantly to said belt for the purposes stated, said means comprising rack bars carried by the supports, a shaft with a pinion connecting said bars and in virtue of which the rotation of said shaft will cause movement of said rack bars in one direction or the reverse accordingly as said pinion shaft is rotated in one direction or the reverse, and means continuously acting on said shaft to turn it in a direction to effect a separation of said pulleys for the purposes described, said acting means comprising a worm gear on said shaft, a worm shaft with a worm meshing with said worm gear and means continuously tending to turn said worm shaft in one direction, and including a constant predetermined force.

13. In a spirally wound tube making machine, a mandrel, an endless spinning belt wound around the mandrel, a pair of belt pulleys, slideable supports for the pulleys and means to apply tension constantly to said belt for the purposes stated, said means comprising rack bars carried by the supports, a shaft with a pinion connecting said bars and in virtue of which the rotation of said shaft will cause movement of said rack bars in one direction or the reverse accordingly as said pinion shaft is rotated in one direction or the reverse, and means continuously acting on said shaft to turn it in a direction to effect a separation of said pulleys for the purposes described, said acting means comprising a worm gear on said shaft, a worm shaft with a worm meshing with said worm gear and means continuously tending to turn said worm shaft in one direction and including a constant predetermined force, and other means to turn said worm shaft in the reverse direction for the purposes described.

55. JAMES BALTON.
